UNITED STATES PATENT OFFICE

WILLIAM H. BOSTON AND CECIL E. BOSTON, OF WINNEBAGO, MINNESOTA

OIL BURNER

Application filed January 24, 1927. Serial No. 163,225.

This invention relates to oil burners and more particularly to oil or burner rings for such burners.

With burners now in use the burner ring is 5 permanently attached to and affixed to the base of the burner being cast with the burner in one piece thereby preventing the removal of the ring for the cleaning thereof, and should the ring require repairing it is necessary to replace the entire burner.

A primary object of this invention is to overcome these disadvantages and provide a burner with a ring constructed to be raised above the fire pot thus effecting a saving of 15 fuel and which is also removable for cleaning and repairs and which is so constructed as to be connected with the burner by the nipple through which oil is supplied.

In carrying out these objects the invention 20 is susceptible of modification without departing from the spirit or sacrificing any of the advantages of the claimed invention; there being shown in the drawings for illustrative purposes a preferred and practical form in 25 which,

Figure 1 represents a side elevation of an oil burner constructed in accordance with this invention,

Figure 2 is a plan view of the burner with 30 the cover member removed,

Figure 3 is a transverse vertical section through the burner,

Figure 4 is a similar view of the burner taken on a plane at right angles to the view 35 shown in Figure 3 with the top or cover removed; and

Figure 5 is a detail sectional view, taken on the line 5-5 of Figure 3.

In the embodiment illustrated the burner 1 40 comprises a fire box 2 bowl-shaped in form with a laterally extending flange 3 at its upper end, and a centrally disposed threaded aperture 4 in its bottom in which is mounted a nipple 5 which projects at its inner end beyond the bottom of the fire box 2 and is 45 designed to receive and support a removable ring 10. This ring 10 is made truncated-cone shape in form and has a central passage 11 opening through the apex thereof, the 50 lower end of said passage being threaded for

connection with the nipple by means of which the ring is detachably mounted and connected with the bowl 2. This ring 10 is provided with a plurality of annular stepped oil grooves 12 such as are ordinarily used in 55 burners of this kind. The removability of this ring provides for the cleansing of these grooves as well as the replacement of the ring should it become injured and require repairing. It also permits changing of the ring 60 from time to time as may be necessary according to the use of the burner.

It will thus be seen that the peculiar construction and mounting of the burner ring 10 to provide for its ready removal and application, when desired, constitutes an important 65 feature of the invention.

The fire box or bowl 2 is provided at diametrically opposite points with air inlet openings 6 and 7 shown triangular in cross-section and having correspondingly shaped collars surrounding the openings and extending upwardly into the bowl with seats 8 arranged around the upper edges thereof on which a removable cover member or cap 15 is designed 70 to be seated. This member 15 is shaped as shown in Figures 1 and 3 of the drawings providing a hollow casing having in its bottom an opening 16 arranged directly over the apex of the burner ring 10, and depending 75 hollow arms 17 the ends of which are designed to rest on the seats 8 over the openings 6 and 7 for a purpose to be described. The hollow member 15 forms an air supply chamber or 80 cap, the air being admitted through the openings 6 and 7 and passes down through the opening 16 in the cap where it mixes and 85 burns with the gas generated by the oil flowing over ring 10. This burned gas passes out around the cap 15 into the furnace and out 90 through the smoke stack.

A solid block-like member 9 is formed at the inner end or corner of opening 7 and has a threaded socket 13 in its lower face to receive 95 a pipe, not shown, for discharging the overflow oil from the burner which enters the pipe through a lateral passage 14. This overflow is provided in case the flame should go out and the oil continue to run in, and the excess oil 100 may be conducted to any desired point.

In the use of this burner the parts being in the position shown in Figures 1 and 3, oil is admitted through the opening 4, nipple 5 and passage 11 and flows down over the grooved face of the ring 10 in a thin film where it contacts with the air admitted through the opening 16 in cap 15.

Should the ring 10 become carbonized and require cleaning all that is necessary is to lift off the cap 15 and unscrew the ring 10 from the nipple 5 and, if desired, another burner ring may be substituted and the burner continue to operate while the old ring is being cleaned. The truncated-cone shape of the burner ring raises the oil retaining space thereof above the bottom of the fire pot and thus keeps the ring hotter to facilitate generation of vapor thereby effecting a saving of fuel.

Without further description it is thought that the features and advantages of the invention will be readily apparent to those skilled in the art, and it will, of course, be understood that changes in the form, proportions and minor details of construction may be resorted to, without departing from the spirit of the invention or the scope of the claim.

We claim:—

An oil burner having a fire box with an opening therein, a burner ring removably mounted over said opening, said box having openings on opposite sides of said ring surrounded by upstanding collars, a block-like member formed at one side of one of said openings and provided with a pipe receiving socket having a laterally extending passage opening into the fire box above the bottom thereof forming an overflow for excess oil, and a hollow casing-like cap cover mounted over said fire box and having depending hollow arms communicating with the openings at opposite sides of the burner ring and having an opening arranged directly over the burner ring whereby air is admitted through said arms and discharged above said ring, said fire box being open on opposite sides of said cap.
